UNITED STATES PATENT OFFICE.

CHARLES W. KNIGHT, OF MINNEAPOLIS, MINNESOTA.

AUTOMATIC STORM-SASH OPERATOR.

Application filed August 16, 1922; Serial No. 582,285.

To all whom it may concern:

Be it known that I, CHARLES W. KNIGHT, a citizen of the United States, residing at Minneapolis, in the county of Hennepin and 5 State of Minnesota, have invented certain new and useful Improvements in Automatic Storm-Sash Operators; and I do hereby declare the following to be a full, clear, and exact description of the invention, such as 10 will enable others skilled in the art to which it appertains to make and use the same.

My invention relates to automatic storm sash operators of the type which connects an inside sliding window sash to a swinging 15 storm sash, whereby the opening and closing movements of the window sash will impart like movements to the storm sash, thus avoiding the effort and inconvenience 20 of opening and closing the storm sash independently of the opening and closing of the window sash.

There are numerous devices on the market intended to open, close and fasten a swinging storm sash, but all are more or less objectionable or imperfect in certain ways. 25 Most of these devices require separate operations, from those to open or close a sliding window sash, for opening and closing a storm sash, and do not provide for opening 30 the storm sash to any fractional degree desired and holding the same firmly in such position. Those devices that do provide for operating a storm sash from a sliding window sash do not provide for a direct outward 35 push, from the window casing, on the storm sash in the direction it swings open; nor do they provide for a direct inward pull, from the window casing, upon the storm sash in the direction it swings closed, 40 and thus do not have sufficient force to infallibly open the storm sash; if it is stuck, swollen, or frozen to the window frame in 45 which it is mounted, nor do they infallibly close the storm sash upon its seat in the window frame, if it tends to stick.

The primary object of my invention is to 50 overcome the above deficiencies and provide an operator that will exert a positive increased pressure on the storm sash directly outward from the window casing, during the initial opening movement, to start the storm sash from its seat in the window frame in which it is mounted, and will also exert a positive increased pressure 55 on the storm sash directly inward toward

the window casing during its final closing movement to draw the same into its seat. A further object of the invention is to apply a direct pushing force to the storm sash in the direction it swings open, and to apply 60 a direct pulling force thereto in the direction it swings closed. A still further object of the invention is to provide a storm sash operator that will firmly hold such a sash in position, whether closed, open, or 65 in an intermediate position and which operator may be easily and quickly attached to or detached from the inside sliding window sash. A still further object of the invention is to insure that the storm sash may never 70 be negligently left open when the inside sliding window sash is closed.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary view of a window frame in which is mounted an inside sliding lower window sash and a swinging storm sash to which sashes the invention is applied;

Fig. 2 is a view corresponding to Fig. 1 with the exception that the two sashes are open;

Fig. 3 is a fragmentary detail view with some parts sectioned on the line 3-3 of Fig. 2, on an enlarged scale;

Fig. 4 is a fragmentary detail view with some parts sectioned on the line 4-4 of Fig. 2, on an enlarged scale; and

Fig. 5 is a detail view in section taken on the line 5-5 of Fig. 1, on an enlarged scale.

The numeral 6 indicates a window frame, as an entirety, with the exception of its water table 7 and parting strip 8 between 100 upper and lower vertical sliding window sashes, only the latter of which is shown and indicated by the numeral 9. This window frame 6 has an outside casing 105 which affords an endless stop against which 110 a storm sash 11 is seated, when closed, and which storm sash is attached, at its upper end, to said casing by the customary separable hinges, not shown, for outward swing 115 movement. The lower horizontal edges

of the two sashes 9 and 11 are beveled to snugly fit against the water table 7 when said sashes are closed. The parts thus far described are all of standard construction 5 and have been illustrated simply for the purpose of showing the invention applied in working position.

Referring now, in detail, to the improved automatic storm sash operator, the numeral 10 12 indicates a bell crank having offset arms, one of which affords a cam-acting latch 13 and the other of which affords a crank arm 14. A latch-actuating rod 15 has one of its ends attached to the crank arm 14 by bending 15 the same laterally to afford a trunnion 16 mounted in an eye 17 formed in the free end of said crank arm. This trunnion 16 is flanged at 18 to prevent its removal from the eye 17. The bell crank 12, at its intermediate portion, is mounted on a bearing plate 19 and pivotally secured thereto by a relatively narrow hinge strap 20 which overlies the intermediate portion of said bell crank between the latch 13 and crank arm 14. 20 Said bearing plate 19 and hinge strap 20 rest, the latter upon the former and the former upon one of the stiles of the swinging sash 11, and are secured thereto by a pair of wood screws 21. The upper end portion of 25 the bearing plate 19 is extended above the hinge strap 20 and bent obliquely to afford a stop 22 for the crank arm 14.

The other or lower end of the latch-actuating rod 15 is pivotally attached to an anchor plate 23 which, in turn, is secured by screws 24 to the sliding window sash 9 below the bearing plate 19. In securing the bearing plate 19 to the swinging sash 11, one of its vertical edge portions is closely positioned 30 to the casing 10, and to align and properly position the anchor plate 23 to the sliding sash 9 in respect to the bearing plate 19, said anchor plate is provided with a pair of vertically spaced prongs 25, the free ends of 35 which are closely positioned to the parting strip 8. On the vertical edge of the anchor plate 23 between the prongs 25, is an outstanding bearing flange 26, and on the other vertical edge of said anchor plate, is an outstanding guard flange 27 having, at its intermediate portion, a notch-like passageway 28. The latch-actuating rod 15, at its lower end portion, extends between the two flanges 26 and 27 and is laterally bent to afford a trunnion 29 which is mounted in a bore-like seat 30 in the bearing flange 26 and transversely aligned with the passageway 28.

This trunnion 29 is free for removal from its seat 30 by a lateral movement of the 40 latch-actuating rod 15, but is held against such removal by the guard flange 27 except when said rod is opposite the passageway 28, and at which time the latch-actuating rod 15 is in a horizontal position, as shown 45 in Fig. 2.

Co-operating with the latch 13 is an abutment 31, secured, by screws 32, to the medial surface of the casing 10 and having a pocket 33 in which said latch extends when the sashes 9 and 11 are closed. This pocket 70 33 is formed by upright laterally spaced inner and outer flanges 34 and 35, respectively, on the vertical edges of the abutment 31, and which flanges extend transversely of the movement of the latch 13. It is important 75 to note that the outer flange 35 is relatively short in comparison with the inner flange 34 and terminates short of each end of said flange 35.

A U-shaped retaining spring 36 for holding the latch 13 in a predetermined position, when the sashes 9 and 11 are open, is attached to the stop 22 by inserting its prongs in notches formed in the upper horizontal edges of said stop and with its transverse portion extending along the back of said stop. The free ends of the prongs of the retaining spring 36 are drawn together and are free to slide, the one upon the other, and are located midway between the latch 13 and 80 crank arm 14. The prongs of the retaining spring 36 are outwardly bulged to afford humps 37, one of which is engaged by the crank arm 14 during the opening and closing movements of the sashes, to move said 85 spring out of the path of the movement of the crank arm 14. When the sashes 9 and 90 11 are open, the hump 37, adjacent to the crank arm 14, holds said crank arm against the stop 22 and which crank arm, in turn, holds the latch 13 raised in a position to pass over the outer flange 35 and into engagement with the inner flange 34 during 95 the closing movement of the sashes.

While only one of the automatic storm 100 sash operators has been shown in the drawings, it is, of course, understood that there will be two employed, in actual usage, on each storm sash. The anchor plate 23 and abutment 31 are so designed that they may 105 be used either on the left-hand or right-hand side of a window, simply by turning the same, end for end. The bell crank 12 must be made in lefts and rights and used on the respective stiles of the swinging sash, but 110 the bearing plate 19 and hinge strap 20 may be used on either of said stiles. The retaining spring 36 is so designed that one of the humps 37 will always engage the crank 115 arm 14 in either of its reversed positions.

The operation of the improved storm sash operator may be briefly described as follows:

As previously stated, when the window sash 9 is in a raised position, the storm sash 11 is securely held open and against rattle, by the improved operator, and at which time, the latch-actuating rod 15 is in a horizontal position and the latch 13 held raised by the crank arm 14, which, in turn, is held 125 raised against the stop 22 by the retaining 130

spring 36. In lowering the window sash 9 to close the same, the storm sash 11 is simultaneously drawn toward a closed position by the improved operator, and, when nearly closed, the latch 13 passes over the flange 35, engages the flange 34, which cams said latch into the pocket 33, swings the bell crank 12 on its hinge and releases the crank arm 14 from the retaining spring 36 and, during the final closing movement of the window sash 9, the rod 15 swings the latch 13 into camming engagement with the outer flange 35, which, with greatly increased force over the previous pulling action on the storm sash 11 to close the same, draws said storm sash with a direct pull into its seat in the window frame 6. With the operator in this position, the storm sash 11 is securely held locked in a closed position.

20 When the window sash 9 is opened, the initial lifting movement thereof, acting through the latch-actuating rod 15, will swing the bell crank 12 on its hinge and bring the latch 13 into camming engagement 25 with the flange 34, and thereby, with great force, which is applied directly to the storm sash 11, will force the same from its seat in the window frame. This movement of the latch 13 is limited by its engagement with 30 the stop 22, which positions the latch 13 to be releasably held by the retaining spring 36.

After the bearing plate 19 and hinge strap 20 are once secured to the storm sash 11 and the parts carried thereon, and the anchor plate 23 secured to the sliding sash, and the abutment 31 secured to the window casing, said parts are permanent and do not have to be changed. In applying the storm sash to the window frame and removing the same therefrom, it is only necessary to hold the same in an open position, so that the rod 15 is exactly horizontal after it is attached to the window frame by its separable hinges, and move the free end portion of 45 the latch-actuating rod 15 laterally through the passageway 28 to insert its trunnion 29 into the seat 30 or remove the same therefrom, as the case may be.

I do not wish to be confined to the precise manner of mounting the fastening device illustrated herein or to the shape of the fastening bar or the cam-acting latch, as in various ways the details may be modified and still be within the scope of my invention.

55 The above described invention has, in actual usage, proven highly efficient for the purpose had in view.

What I claim is:

1. The combination with a window frame, 60 a sliding sash and a swinging sash mounted in the window frame, of a pivoted cam-acting latch on the swinging sash, a latch-actuating rod attached to the sliding sash, and an abutment on the window frame with 65 which said latch engages during the open-

ing and closing movements of the sliding sash to impart respective opening and closing movements to the swinging sash.

2. The structure defined in claim 1 in further combination with a stop for limiting the movement of the pivoted cam-acting latch during the opening movement of the sliding sash.

3. The structure defined in claim 1 in further combination with means for releasably holding said latch during the opening movement of the sliding sash and from which means said latch is released by the final closing movement of the sliding sash.

4. The structure defined in claim 1 in further combination with a stop for limiting the movement of the pivoted cam-acting latch during the opening movement of the sliding sash, and means for releasably holding said latch when positioned by the stop and from which means said latch is released by the final closing movement of the sliding sash.

5. The combination with a window frame, 90 a sliding sash and a swinging sash mounted in the window frame, of a pivoted cam-acting latch on the swinging sash, a latch-actuating rod attached to the sliding sash, and an abutment on the window frame and having a pocket in which said latch projects when said sashes are closed, said latch being arranged to engage the abutment when the sliding sash is raised to impart the initial opening movement to the swinging sash and to position said latch to enter said pocket during the final closing movement of said sashes, said latch also being arranged to engage the abutment during the closing movement of the sashes to impart the final closing movement to the swinging sash. 95

6. The structure defined in claim 5 in further combination with a stop for limiting the movement of the pivoted cam-acting latch during the opening movement of the sliding sash, and a retaining spring for releasably holding said latch when positioned by the stop and from which retaining spring said latch is released by the final closing movement of the sliding sash. 110

7. The combination with a window frame, 115 a sliding sash and a swinging sash mounted in the window frame, of a pivoted cam-acting latch having a crank arm, a latch-actuating rod connecting said arm to the sliding window sash, and an abutment on the window frame having a pocket into which said latch projects when said sashes are closed, said latch being arranged to engage the abutment when the sliding sash is raised to impart the initial opening movement to the swinging sash and to position said latch to enter said pocket during the final closing movement of said sashes, said latch also being arranged to engage the abutment during the closing movement to the sashes to impart 120

125

130

the final closing movement to the swinging sash.

8. The structure defined in claim 1 in further combination with a stop for limiting the movement of the pivoted cam-acting latch during the opening movement of the sliding sash, and a retaining spring having a hump over which a part on said latch moves during the opening and closing movements of said sashes, said hump being adapted to releasably hold said latch in a prede-

termined position after the initial opening movement of the sashes and from which hump said latch is released by the final closing movement of the sliding sash. 15

9. The structure defined in claim 8 in which the retaining spring is provided with two humps and in which the latch is reversibly held in respect to the retaining spring. 20

In testimony whereof I affix my signature.
CHARLES W. KNIGHT.
